UNITED STATES PATENT OFFICE.

ADRIAN R. PYLE, OF DOBBS FERRY, NEW YORK.

GAS-COCK.

1,078,875.

Specification of Letters Patent. Patented Nov. 18, 1913.

Application filed June 18, 1912. Serial No. 704,264.

To all whom it may concern:

Be it known that I, ADRIAN R. PYLE, a citizen of the United States, and a resident of Dobbs Ferry, county of Westchester, 5 State of New York, have invented certain new and useful Improvements in Gas-Cocks, of which the following is a specification.

My invention relates to an automatic or 10 safety gas cock which may be readily opened to any degree, but which closes positively and is automatically held in closed position, thus effectually preventing any accidental opening which might result dis- 15 astroously.

My invention can readily be adapted for use with any gas fixture, replacing the usual stop cock, and is simple in construction and operation.

20 In the accompanying drawings which form a part of this specification, Figure 1 is a sectional view showing my improved device with the valve in closed position. Fig. 2 is a similar view with the valve open.

25 Referring to the drawings in detail, the numeral 1 designates the house service pipe projecting from the house wall 2 and terminating in an externally threaded portion 3 upon which is screwed the fixture 4. 30 This fixture includes the pipe elbow 5, in one end of which is the screen 6. The other end terminates in a barrel 7 for the reception of a valve device and from this barrel branches the pipe 8, to which is secured 35 the burner 9 and tip 10. The elbow is enlarged where it meets the barrel to form a conical seat 11 for the conical valve 12, which has the piston portion 13 fitting snugly within the barrel. A stem 14 affixed 40 to the lower portion of the piston passes through a metal washer 15, felt washer or packing 16 and cap 17 mounted upon the lower end of the barrel. The stem terminates in a beaded or ratchet portion 18 45 adapted to engage with a pawl 19 pivoted at 20 to the stationary arm 21 forming a part of the bracket. Within the barrel

and surrounding the stem is a spring 22 which normally acts to force the valve against its seat.

50 When it is desired to light the gas, the valve is opened by pulling down the handle 23 and the gas is thereby permitted to pass through the valve in the direction of the arrow in Fig. 2, and so into the burner. 55 When the valve is opened to the desired extent, the pawl is brought up into engagement with the ratchet or beaded surface, as shown in Fig. 2, and thus caused to hold the valve open against the force of the 60 spring. The closing of the valve is effected by tripping the pawl, whereupon the spring will cause the valve to seat and positively shut off the gas supply.

65 While I have illustrated and described only two embodiments of my invention, I realize that it is susceptible of wide variation and I do not desire to be limited to the precise structure set forth and described.

Having thus described my invention, I 70 claim:

1. A gas cock comprising a reciprocating valve, means normally tending to close said valve, a serrated stem attached to the valve head, and means for locking the valve open 75 in a plurality of positions, including an arm pivoted to a fixed member and having a claw on one end adapted to engage said stem.

2. A gas cock comprising a reciprocating 80 valve, means normally tending to close said valve, a serrated stem on said valve, and means engaging said stem for locking the valve open in a plurality of positions, said means including an arm pivoted to a fixed member and having a claw on one end 85 adapted to engage said stem, the center of gravity of said arm lying between the claw and the point at which the arm is pivoted.

ADRIAN R. PYLE.
